(57) **CLAIM**

The ornamental design for a gas manifold system as shown and described.

DESCRIPTION

FIG. 1 is a left front perspective view showing the ornamental design of the claimed gas manifold system;

FIG. 2 is a front view thereof;

FIG. 3 is a back view thereof;

FIG. 4 is a right side view thereof;

FIG. 5 is a left side view thereof;

FIG. 6 is a bottom side view thereof; and,

FIG. 7 is a top side view thereof.

In FIGS. 6 and 7, the dash-dash broken lines are for the purpose of illustrating portions of the gas manifold system that form no part of the claimed design.
